(57) **CLAIM**

The ornamental design for a tennis elbow support, as shown and described.

DESCRIPTION

FIG. 1 is a perspective view of a tennis elbow support, showing our new design, in use condition;

FIG. 2 is a top view thereof;

FIG. 3 is a bottom view thereof;

FIG. 4 is a side view thereof, the opposite side view being a mirror image;

FIG. 5 is a back end view thereof; and,

FIG. 6 is a front end view thereof.

The broken line showing of the limb is for illustrative purposes only and forms no part of the claimed design.
